SAMUEL FURMAN, OF WORCESTER, MASSACHUSETTS, ASSIGNOR TO UNITED STATES ENVELOPE COMPANY, OF SPRINGFIELD, MASSACHUSETTS, A CORPORATION OF MAINE.

MACHINE FOR MAKING WINDOW-ENVELOPS.

1,381,090.

Specification of Letters Patent. Patented June 7, 1921.

Continuation of application Serial No. 45,506, filed August 14, 1915. This application filed August 24, 1917. Serial No. 187,980.

To all whom it may concern:

Be it known that I, SAMUEL FURMAN, a citizen of the United States, residing at Worcester, in the county of Worcester and 5 Commonwealth of Massachusetts, have invented a new and useful Improvement in Machines for Making Window-Envelops, of which the following, together with the accompanying drawings, is a specification.

10 The present invention relates to improvements in a machine for making window envelopes, this application being a continuation of my copending application Serial No. 45,506, filed August 14, 1915. The machine 15 of the present invention contemplates the provision of mechanism for feeding initially cut window envelop blanks into and through the machine, suitable instrumentalities being provided for first cutting a window 20 opening in the blank, then gumming around the margin of said window opening and along that edge of the blank which constitutes the back flap of the envelop. Thereafter, the machine applies a patch or panel 25 of transparent material to the gummed window opening to cover the same, after which the end flaps of the blank are folded inwardly, and the back flap, already gummed, is folded down over said end flaps to complete 30 the pocket or inclosure. In its further progress through the machine the extended seal flap of the envelop thus partly formed, is gummed along its free edge, and thereafter said seal flap is creased or turned 35 over toward the back of the envelop, but is prevented from making contact therewith.

The invention resides in the provision of a novel combination of instrumentalities for accomplishing the foregoing objects, as well 40 as additional mechanism for automatically rendering inoperative the seal flap gumming mechanism when no blank is forwarded thereto. The novel features of my invention are fully set forth in the following description 45 and in the annexed claims, reference being had to the accompanying drawings, in which Figure 1 is a side elevation of the machine embodying my inventions.

Fig. 2 is a top plan view of the same, with 50 parts removed.

Fig. 3 is a longitudinal sectional view of the machine.

Fig. 4 is an end view looking from the right in Figs. 1, 2 and 3, and omitting, for

the sake of clearness, the seal flap gumming mechanism.

Fig. 5 is a detail view of the mechanism for rendering inoperative the seal flap gumming mechanism.

Fig. 6 is a cross sectional view of a portion 60 of the folding mechanism.

Fig. 7 is a fragmentary plan view of the folding mechanism.

Fig. 8 is a sectional view on the line 8—8, 65 of Fig. 7.

Fig. 9 is a fragmentary sectional view on the line 9—9, of Fig. 7.

Fig. 10 is a detail view of the seal flap gumming mechanism.

Similar reference characters refer to like 70 parts in the different figures.

Referring particularly to Figs. 1, 2 and 3, the mechanisms constituting my invention are carried by frames 1, 1, and auxiliary superposed frames 2, 2. A main driving 75 shaft 3 is journaled in these frames, and carries a driving pulley or other actuating means, shown at 3', for transmitting power to the several mechanisms.

The envelop blanks are fed forward in the 80 machine by means of an initial feeding mechanism which advances them successively to the point in the machine where they are punctured to form a window opening. This initial feeding mechanism may be of any 85 well known construction, and in the present instance I have shown the same as consisting of a plurality of feeding disks 4, 4, carried on a shaft 5, said disks coöperating with disks 6, 6, on a shaft 7. The shafts 90 5 and 7 are geared together to rotate in unison, and are driven by suitable gearing, not shown, from the main driving shaft 3. In advance of the feeding disks 4 and 6 are disposed upper and lower feed rolls 8 95 and 9 which are carried on shafts 10 and 11 respectively, and which feed the blank, as shown by the broken lines 12, Fig. 2, onto a skeleton support 13.

Below said support, and near the outer 100 edges of the blank, as shown in Fig. 2, are provided a pair of laterally spaced disks 14, 14, carried on a shaft 15. Said disks 14 each have a segmental portion 16 of the periphery cut away, as shown in Figs. 1 105 and 3, and the shaft 15 is so timed with respect to the advance of the blank that these cut away portions 16 are brought upper-

most beneath the blank, as the latter arrives on the support 13. For coöperation with the disks 14 I provide a corresponding pair of suitably journaled rolls 17, which are designed to make rolling contact with the unrecessed peripheries of disks 14, but which are inoperative when the cut away portions 16 thereof pass beneath the blank. As a consequence each blank upon its arrival on the support 13, has its forward motion arrested during the passage therebeneath of the cut away portions 16 of the disks 14; after this momentary stoppage, due to the stops 32, as hereinafter described, the advance of the blank is continued by the co-operation of disks 14 with rolls 17. The shaft 15 is continuously rotated by suitable gearing, Fig. 2, from the main driving shaft 3. During the stoppage of the blank on support 13, a window is cut therein, as shown in Fig. 2. To this end, the shaft 15 is inclosed loosely within an elongated slot 18 in a sliding block 19, the lower end of which is guided in a bracket 20 of frame 1. The block 19 may be further guided by means of adjustably mounted rollers 21, which bear against opposite sides of an extension 22 of said block, in order to insure the parallel reciprocation of the same. The block 19 is reciprocated by means of a pair of cams 23 and 24 on shaft 15, one cam 23 coöperating with a roller 25 to lower the block, and the other cam 24 coöperating with a roller 26 to raise the block.

The block 19 carries on its upper end a male die or punch 27. For coöperation with the male die 27, the machine provides a female die 28, disposed above the blank in a stationary support 29, the latter being open as at 30, for the passage of the waste paper resulting from the punching operation of the die 27, at each reciprocation of block 19. Thus each blank brought to rest on the support 13 has a window opening cut therein, as shown by the full line 31, Fig. 2.

In order to register each blank in exact position for the cutting of this window opening, I preferably provide a pair of oscillating stops 32 which may conveniently take the form of inwardly and downwardly bent bars or wires 33, adjustably secured in sockets 34 on a rock shaft 35; the latter is oscillated by means of a rock arm 36, pivotally connected to a forked link 37, the other end of which embraces and is guided by the shaft 15. Said link 37 carries a roller 38 for coöperation with a cam 39 on shaft 15. As the blank is moved onto the support 13 by the feed rolls 8 and 9, the stops 32 are depressed so as to lie in the path of its advancing edge, being arranged for reception in the reentrant angles which define the line of fold of the back flap, as shown in Fig. 2. After the window opening is cut, as above

described, and just before the disks 14 and rollers 17 become effective in continuing the forward movement of the blank, the stops 32 are raised out of the path of the blank by the oscillation of rock shaft 35, under 70 the influence of cam 39.

The disks 14 and roller 17 then advance the blank into the bight of coöperating pairs of feed disks 40 and 41 which are suitably driven by gearing, Fig. 2, from the main 75 driving shaft 3. In advance of said feed rollers, the machine provides a cylinder 42, which is mounted on a rotating shaft 43 below the blank, and driven by suitable gearing from the main shaft 3. This cylinder 80 42 coöperates with a pair of upper feed disks 44 for continuing the forward movement of the blank, said disks being spaced apart laterally in substantial alinement with the disks 14 so as to make contact with the 85 blank beyond the limits of the back flap and beyond the limits of the window opening. The disks 44 are mounted on a shaft 45 which is geared to rotate in unison with, and at the same speed as the shaft 43. 90

Said shaft 45 has secured thereto a gumming segment 46 which carries an angular gumming die 47 corresponding in contour to the edge of the back flap and an annular gumming die 48 corresponding in contour to the margin of the window opening 95 in the blank. A gum-transferring roller 49 of usual construction is disposed in the path of the gumming dies 47 and 48, and is adapted to apply, at each revolution of shaft 45, a 100 coating of gum thereto. The roller 49 is in continuous contact with a gumming cylinder 50 which rotates partially submerged in a gum box 51 carrying a supply of liquid adhesive. In this way the edge of the back 105 flap, and the margin of the window opening in each blank are supplied with moist adhesive during the passage of the blank through the machine, without arresting its forward movement. The cylinder 42 effectually supports the blank during this 110 gumming operation.

The advance of the gummed and cut blank is continued by the cylinder 42 and coöperating disks 44, and also by pairs of feed 115 rollers 52, 52, which are suitably spaced apart laterally so as not to make contact with the gummed portions of the blank's surface. These rollers 52, as well as the rollers 40 and 41 are supplemented, if necessary, by 120 suitable guiding devices 53 and 54, on opposite sides of the blank, which prevent sagging or deflection of the extended surfaces or flaps thereof, in the manner common in machines of this class. The rollers 52 project each blank successively onto a stationary table or support 55, with the advancing end of back flap of the blank overlying a plate or member 57, as shown in Fig. 2. Each blank is brought to rest on said table 55 by 130

means of a pair of stops 56 which are laterally spaced apart to correspond to the reentrant angles of the advancing edge, which angles define the line of fold of the back flap. These stops 56 project rearwardly from the member 57 which is carried by a rock shaft 58. The rock shaft 58 is actuated through a rock arm 59, which is pivotally connected to a forked link 60, the other end of which embraces and is guided by a continuously rotating shaft 61, hereinafter more particularly referred to. This shaft 61, which is driven by suitable gearing from the main driving shaft 3, carries a cam 62 which operates against a roller 63 on the forked link 60, to rock the shaft 58 at appropriate intervals. The above described mechanism is timed so as to interpose the stops 56 in the path of the blank, just as the latter arrives on the table 55, thereby effectually registering said blank in proper position for the application of a patch thereto, and for the operations of folding the side and back flaps thereof, as hereinafter described.

For the purpose of exact registration, to prevent the rebound of the blank after impact with the stops 56, I provide a pair of spaced arms 64, 64, journaled on a rock shaft 65, and constrained to move with said shaft by means of attached springs 64', 64', Fig. 5. The arms 64 are normally in the position shown in Fig. 6, until a blank has passed onto table 55. As soon as a blank arrives on said table, and strikes against the stops 56, the shaft 65 is rocked, to carry the arms 64 from the position shown in Fig. 6 to the position shown in Fig. 3, where the upper ends of said arms enter slots 55', and are brought to rest by their adjustable stops 65', approximately within the reentrant angles on the rear edge of the blank, which angles define the line of fold of the seal flap. The rotation of shaft 65 continues, for a purpose hereinafter described, the springs 64' permitting this movement, and pins 64" on said shaft serving to return the arms, on the reverse oscillation of the shaft. The shaft 65 has secured thereto a rocking arm 66 which is pivotally connected to a forked link 67. The free end of the latter embraces and is guided by a shaft 68 which is rotated continuously through suitably timed gearing, Fig. 2, from the main driving shaft 3, said shaft 68 having a cam 69 thereon which co-operates with a roller 70 on link 67 to impart suitably timed oscillations to the shaft 65. In this way the blank is registered and squared by the conjoint operations of stops 56 and arms 64 in position for the application of a transparent patch thereto. The patch material is fed from a suitable supply roll 71 which is carried on a spindle 72. The material is advanced between feed rolls 73 and 74, which operate intermittently, in con-

junction with cutting devices 75 and 76 to produce patches of predetermined length, for application to successive blanks.

The mechanism herein shown for intermittently feeding the patch material and for cutting the same between the stationary member 75 and the reciprocating member 76, is substantially the same as the corresponding mechanism shown in my United States Letters Patent No. 1,182,364, granted May 9, 1916; said mechanism by itself forms no part of the present invention, and therefore a detail description thereof is unnecessary. It is to be understood that any suitable patch cutting and feeding devices may be employed in this connection.

The patches thus fed forward and cut off are deposited on a pair of arms 77, projecting from a rock shaft 78. Said rock shaft has an operating rock arm 79, which is pivotally connected to a forked link 80, the latter at its free end embracing and being guided by the shaft 45 which carries the gumming devices 47 and 48 heretofore referred to. Said shaft 45 carries a cam 81 which co-operates with a roller 82 on link 80 to impart the desired oscillations to rock shaft 78, whereby the arms 77 are held in horizontal position, to receive a transparent patch from the patch feeding and cutting devices, and to hold said patch in the path of a vertically reciprocating member 83. The movable member 76 of the patch cutting mechanism above described is operable by a link 84 and arm 85, said link being pivotally attached to a lever 86, pivoted at 87, and having a cam roller 88 for co-operation with a cam 89 on shaft 68, as shown in Fig. 1.

The member 83 is reciprocated in a fixed guide 90 by means of a swinging lever 91 which is pivoted at 92 in the frame-work 2 and has a link connection 93 with said member. A forked arm 94 is pivotally connected to the swinging lever 91, and its other end embraces and is guided by the shaft 68, said arm carrying a cam roll 95 which co-operates with a cam 96 on said shaft 68. The member 83 is hollow, and provides on its lower operating face 97, Figs. 1 and 4, a plurality of apertures 98, communicating with its interior. The interior of said member 83 is connected by a flexible connection 99 with a suitable exhaust apparatus, not shown, by means of which a partial vacuum may be created at will through said member. With the member 83 in its uppermost position, as shown in Fig. 1, the arms 77 are in horizontal position, and support a severed patch of transparent material in the path of said member. The descent of said member 83 depresses said arms, the curvature of cam 81 permitting this action, and the suction through said member 83 causes the patch to be seized and held by the lower operating face 97 of member 83. The patch is thus 130

transferred from the arms 77, on which it has rested by gravity, to the under face of the member 83, against which is held by suction, and the further descent of said member 5 carries said patch downward into contact and registration with the window opening of the envelop blank which has come to rest on the table 55.

As the member 83 carries the patch into 10 contact with the gummed margin of the window opening in the blank, the suction through said member and its flexible connection 99 may be released, and if desired, a pressure of air in the opposite direction 15 through said member may be created by the pump or other exhaust apparatus, above referred to, but not shown. At the same time, coincident with the approach of the patch into contact with the blank, the removal of 20 said patch from the reciprocating member 83 is insured by the stripping action of a creasing and forming plate 100 which is carried on arms 101 attached to a rock shaft 102. The rock shaft 102 has an operating arm 103 25 which is pivotally connected by means of a link 104 to a lever 105, pivoted at 106 to the framework 1. A cam roll 107 on lever 105 is acted upon by a cam 108 on shaft 43 to rock the shaft 102 at appropriate intervals, where- 30 by the plate 100 is moved from the position shown in Fig. 6, to the position shown in Figs. 1 and 3, substantially coincident with the approach of a patch toward the window opening of a blank on the table 55.

The plate 100 is skeleton in formation, 35 as shown in Fig. 2, the free edge thereof being suitably recessed as at 109, Figs. 2 and 7, to escape interference with the arms 77 when said plate is in its uppermost position, 40 as shown in Fig. 6. These openings 109 also permit the plate to clear the two depending suction surfaces 97 of the member 83, in the act of stripping the patch from said surfaces as hereinbefore described. As 45 said plate 100 is rocked downwardly into horizontal position, it may press the patch flat against the surface of the blank and cause its adhesion to the gummed margin of the window opening therein, but it is not required that said plate shall exert a suffi- 50 cient pressure to firmly apply the patch to the blank, since this pressing function is taken care of by other parts, as hereinafter described. At the same time, the arrange- 55 ment of parts may, if desired, be such that the free edge of said plate 100 co-operates with the adjacent free edge of member 57, to impart an initial crease along the line of fold between the back flap of the body por- 60 tion of the blank. That is, soon after the plate 100 is lowered, the member 57, over which the back flap extends, is raised, and thereby partially turns up said back flap. This action between the adjacent edges of 65 the plate 100 and member 57 accomplishes

an initial creasing of the blank along the line of fold between the back flap and the body portion of the blank, but it is to be understood that such action is not essential to the operation of my machine, since means 70 are provided as hereinafter described, for completely creasing and folding said back flap at a single operation.

The plate 100 may also be designed to 75 impart an initial crease along the line of fold between the seal flap and the body of the blank. To this end the rearward portion of table 55 has a movable section 110, the same being vertically slidable between integral depending walls 111 and 112 80 of said table. The movable section 110 has depending therefrom at each end a yoke 113, which embraces and is guided by the rock shaft 65. The latter carries cams 114, which, after the arms 64 have been moved into 85 operative position as above described, act on rollers 115 of said yokes to raise and lower the movable section 110 toward and away from the plate 100. Said plate 100 has a projecting transverse spur or edge 116 90 which coincides with the line of fold of the seal flap when said plate 100 is in its horizontal position. A corresponding trans- 95 verse notch 117 in the movable section 110 co-operates with the spur 116 to impart an initial crease or score along said line of fold of the seal flap when said movable section 110 is raised by cams 114 as above described.

This initial creasing of the seal flap takes 100 place substantially coincident with the folding in of the side flaps of the blank, after the patch has been applied to the gummed margin of the window opening, and after the member 57 and stops 56 have been rocked upwardly into the position shown 105 in Fig. 3. The plate 100, in its horizontal position tends to press the body portion of the blank down into contact with the table 55, and the side edges of said plate, which correspond to the lines of fold of the side 110 flaps, act as formers over which said side flaps are folded, as hereinafter described. In this forming position of the plate 100 the side flaps of the blank are deflected 115 slightly upward, because of the interposed thickness of adjacent side flap folding plates 118, 118, Figs. 7 and 8, which are slideable in and out on the surface of table 55, and normally lie beyond the lateral edges of plate 100. In the section shown in Figs. 7 120 and 8, the blank is designated at 119, the rectangular body portion of the same being shown as pressed down firmly upon table 55 by the plate 100, while the side flaps there- 125 of project outwardly over the plates 118.

The plates 118 have depending extensions 120 which project through transversely elongated slots 121 in table 55. Each extension 120 has a vertically elongated slot 122 to receive the trunnion 123 of a pair of rolls 130

124, 124, which travel on the under surface of table 55, as shown in Fig. 9. Said trunnion 123 is pressed toward the top of slot 122 by a compression spring 125 which permits relative movement between the rolls 124 and their plate 118, and thus allows said plate sufficient play to pass over the adjacent edge of plate 100, in the act of folding in the side flap of the blank. To this end 10 the side edges of the plate 100 may with advantage be beveled off, as shown at 126, Fig. 8, and the adjacent edges of plates 118 may be undercut, as shown at 127. The plates 118 are moved in and out, to accomplish this folding action by means of levers 128, 128, which have pin and slot connections 129, 129, with the lower ends of extensions 120. Said levers 128 extend rearwardly of the machine and are pivoted at 20 130, 130, to the framework 2 on opposite sides thereof, the rear ends of said levers carrying rolls 131, 131, which are acted upon by face cams 132, 132, on shaft 43, hereinbefore referred to. In this fashion the 25 plates 118 are simultaneously moved inwardly toward each other to fold the side flaps of successive blanks over the adjacent edges of forming plate 100, and are then withdrawn to permit the action of the back 30 flap folding mechanism.

The back flap folding mechanism is incorporated with a rotary carrying mechanism which, simultaneously with the folding of the back flap over the inturned side 35 flaps, removes the partially completed envelop from the table 55 and advances it to the mechanisms for gumming and folding the seal flap, as hereinafter described. To this end the shaft 68 has secured thereto a 40 carrying cylinder 133 with whose periphery the table 55 is substantially tangential, at the forward edge of said table, directly above the shaft 68, as shown in Figs. 3 and 6. The surface of said cylinder 133 provides 45 a longitudinal opening 134 for the operation of a gripper folder 135 which is secured to an oscillating shaft 136 carried by the cylinder 133 in a position eccentric to its axis. The ends of shaft 136 pass through 50 and are journaled in the heads of the drum or cylinder 133, one end of said shaft carrying an arm 137 which provides a roller 138 that is acted upon at a proper period of its rotation about the axis of shaft 68 by a deflecting cam surface 139, thereby rocking the 55 arm 137 to quickly rock said shaft 136 in a counterclockwise direction, Figs. 3 and 6. In order to accelerate this rocking movement the deflecting cam surface 139 is secured on a rocking member 140 which, coincident with the arrival of roller 138 in contact with surface 139, is moved quickly in the opposite direction to said roller by means 60 of a cam 141 on a shaft 142 which is driven 65 through suitable gearing, Fig. 2, from the main driving shaft 3. The cam 141 acts against a roller 143 which is carried by a forked link 144 that embraces and is guided by the shaft 142, the other end of said link being pivotally connected at 145 to the rocking member 140.

This extremely rapid oscillation of the shaft 136 occurs as the cylinder 133 approaches the position illustrated in Fig. 3, with the result that the gripper folder 135 is moved quickly through the opening 134 into the position indicated in said figure. Said gripper folder provides an angular extension 146 which strikes the under side of the back flap, as it approaches the position of Fig. 3, and thereby folds said back flap over the adjacent edge of forming plate 100, at the same time pressing the inner or lower part of the gummed edge of said back flap firmly into contact with the inturned side flaps of the blank. The line of fold of the back flap is pinched and seized by the inner and under portion of angular extension 146, particularly by yielding friction devices 146', such as rubber cushions, 90 acting through openings 109, in conjunction with the peripheral surface of cylinder 133, with the result that the partially folded envelop is drawn off of plate 100 by the continued clockwise rotation of said cylinder, the gripper folder 135 becoming increasingly effective in pressing down the back flap as said rotation is continued. Finally, the roller 138 reaches the end of deflecting cam surface 139, whereupon the gripper folder releases the envelop and 100 springs back to its normal position, shown in Fig. 6, under the influence of a spring 147, which is secured at one end to the shaft 136 and at the other end to an arm 148, 105 through which said shaft loosely passes and which is journaled on shaft 68.

The partly folded envelop thus carried downwardly by the rotation of cylinder 133 is acted upon by a pressing plate 149 of cylindrical contour, which is secured to a cylinder 150, carried by the shaft 61 hereinbefore referred to. The cylinder 150 is of such a diameter as to have its periphery spaced from the periphery of cylinder 133 to allow the passage of the gripper folder 135 on the latter cylinder, but the pressing plate 149 rolls in substantial contact with the cylinder 133, and thereby firmly unites the folded back flap to the inturned side or end flaps, thus completing the rear wall of the envelop, and at the same time firmly uniting the transparent patch to the front wall. Said pressing plate 149 is preferably of such a shape that when developed in a single plane it corresponds approximately to the edge of the back flap of the blank, and said plate is so proportioned that its pressure on the back flap ceases just short of the edge thereof in order 120 125 130 135 140 145 150 155 160 165 170 175 180 185 190 195 200 205 210 215 220 225 230 235 240 245 250 255 260 10000

not to cause the moist gum to exude past said edge.

The cylinder 150 provides an opening 151 in its periphery toward which project a pair of spaced radial arms 152 secured to the shaft 61. These arms 152 are slotted at their outer ends to receive the stem 153 of a seal flap gumming member 154, said stem being radially movable in said slots. To this purpose said gumming member has rollers 155 mounted on trunnions 156 at each end, said rollers being pressed inwardly by springs 156', Fig. 2, into contact with the peripheries of a pair of similar cams 157, which are loosely journaled on the shaft 61, as shown in Fig. 10.

In the normal operation of the machine, the gumming member 154, as rotated by the shaft 61, receives a coating of gum from a transfer roller 158, the latter being continuously supplied from a gumming roller 159 submerged in a gum box 160 of usual construction. In normal position shown in Fig. 10, the contour of cams 157 is such that the gumming member 154 after being extended to make contact with transfer roller 158, as shown, then is drawn inward to lie approximately even and flush with pressing plate 149, and in this position said gumming member lays a coating of gum along the edge of the seal flap of an envelop in transit between cylinders 133 and 150. In this manner the seal flap of each partly finished envelop is gummed, immediately after the pressing action of the plate 149, and thereupon each envelop, being released by the gripper folder 135, passes by gravity, or otherwise, into the bight of feed rollers 161 which advance it to the seal flap folding mechanism, as hereinafter set forth.

It sometimes occurs, however, that, due to a momentary cessation in feeding the blanks, or to any other cause, there is no partly formed envelop passing between the cylinders 133 and 150 when the gumming member 154 reaches its operative position, as above described. Under these circumstances the normal operation of said gumming member would carry it into contact with the surface 50 of cylinder 133, with the result that the succeeding envelops passing through the machine would be soiled and would adhere to the surface of said cylinder, necessitating the stoppage and cleaning of the machine.

To avoid this result, the cams 157 are pivotally connected as at 162 to a link 163 which is operated by an arm 164 extending from a rock shaft 165. Said rock shaft is adapted to be actuated by an arm 166, on 60 the end of which is secured a laterally projecting stud 167, Fig. 5, having loosely mounted thereon for sliding movement a wheel 168. Said wheel is yieldingly pressed against a stop 169 at the outer end of said stud by means of a compression spring 170,

and in this position said wheel is out of the path of a cam 171, which is secured on a shaft 172 that is continuously driven by suitable gearing, Fig. 2, from the main driving shaft 3 of the machine.

70

The movable section 110 of table 55 provides a plurality of apertures, here shown as three in number, for the reception of the upper ends of pins or fingers 173, Fig. 5, and the superposed creasing and forming plate 75 100 has similarly arranged apertures which, in the absence of a blank on table 55, are adapted to receive the upper end of said pins or fingers 173, when the movable section 110 is moved upwardly by the action 80 of oscillating cam 114. These fingers 173 are carried by a block 174, which is supported on the end of a lever 175, pivoted at 176 to a bracket 177 depending from the table 55. The other end of lever 175 is pivotally connected at 178 to a pitman 179 which has a beveled lower end 180 in close proximity to the beveled edge of wheel 168.

85

The pitman 179 is suitably guided for parallel reciprocation by a pin and slot connection with a bracket 181, and is urged downwardly, Fig. 5, by a spring 182 of greater strength than the spring 170 which holds the wheel 168 away from cam 171. However, the spring 182 is not sufficiently strong to 95 depress the pitman when there is a blank on the table 55, since the upper ends of pins 173 will be obstructed by the presence of a blank, and hence the pitman will remain in the position shown in Fig. 5. On the other 100 hand when no blank is present on the table 55, and the movable section 110 is elevated in its usual cycle of movement, the ends of pins 173 will be free to pass into the corresponding apertures in plate 100, under the 105 action of spring 182. This action is accompanied by a depression of the pitman 179 into wedging contact with the wheel 168, thus forcing said wheel inwardly, so as to be acted upon by cam 171. In this manner, 110 when a blank is missing from the table 55, cam 171 is brought into play to rock the shaft 165, and thereby through the arm 164 and link 163 to rotate the cams 157 so that the gumming member 154 controlled by said 115 cams will be drawn inwardly when opposite the cylinder 133, by low portions 157' of the cams, and will have its subsequent outward movement advanced to a point in its travel where it is not directly opposite the 120 cylinder 158. In this manner, the smearing of gum on the cylinder 133 is effectually prevented.

115

The feed rollers 161 are suitably grooved and arranged to avoid contact with the 125 moist gum on the seal flap as the nearly completed envelops pass therebetween and fall by gravity into a V-shaped receptacle constituted by a stationary wall 183 and a swinging wall 184, which is carried on a 130

- rock shaft 185, supported by the framework. The envelops drop into this V-shaped receptacle, with their folded lower ends foremost, and with their gummed seal flaps projecting past the upper edge of wall 184. As each envelop is thus received, the wall 184 is rocked inwardly from the position shown in Fig. 1 to the position shown in Fig. 3, by means of an arm 186 connected to rock shaft 185 and operated by a forked link 187 which embraces and is guided by the shaft 172. Said shaft 172 carries a cam 188 which acts on a roller 189 of the link 187 to rock the shaft 185, and thus brings the extended seal flap of the envelop adjacent to the periphery of a cylinder 190 carried by the shaft 172.
- The cylinder 190 constitutes a conveying mechanism for delivering the envelop from the V-shaped receptacle above described to a drying chain 191 of usual construction, or to any other mechanism of this class for handling the completed envelops, and said cylinder 190 combines with its conveying function, the function of finally turning over or folding the gummed seal flap of the envelop, which preferably has had an initial crease along its line of fold while resting on table 55. To this end the cylinder 190 has a longitudinal opening 192, 25 for the operation therethrough of a gripper folder 193, carried on an oscillating shaft 194 which is supported at its ends by the cylinder 190 in an eccentric position to the shaft 172, and operated in precisely the same manner as the shaft 136 of gripper folder 135. That is to say, the shaft 194 has an arm 195, Fig. 3, which carries a roller 196 that bears on a deflecting cam surface 197, similar to the deflecting cam surface 139 30 above referred to. Said deflecting cam surface 197 is oscillated in the direction opposite to the rotation of cylinder 190 by means of a forked link 198, Figs. 1 and 4, which embraces and is guided by the shaft 142, the latter having a cam 199 which co-operates with a roller 200 on link 198 to impart the proper movement to deflecting cam surface 197. In this way the requisite quick action of gripper folder 193 is obtained, similar to 35 the action of gripper folder 135, whereby the extended seal flap of an envelop, held against the periphery of cylinder 190 by the swinging wall 184, is struck backward by the gripper folder 193, and folded over the edge of said wall 184, during the rotation of cylinder 190. The gripper folder 193 is shaped so as to pinch and seize the envelop only along the line of fold of the seal flap, without pressing the same into contact 40 with the back wall of the envelop and the envelop so pinched and seized is carried around by the rotation of the cylinder 190 until the gripper folder releases the same and swings back into normal position under 45 the influence of a spring 201, Fig. 4. This carries the envelop between the cylinder 190 and a pair of co-operating feed rolls or cylinders 202 which are carried on a shaft 203 that is rotated continuously by suitable gearing from the main driving shaft 3. The cylinder 202 is cut away, as shown at 204, so as to avoid pressing the seal flap into contact with the back wall of the envelop. The cylinders 190 and 202 co-operate in forwarding the completed envelops to the drying chain 191, or other equivalent device, where the seal flap gum is thoroughly dried before the envelops are stacked and boxed.
- The operation of my improved machine will be clear from the detailed description of its component parts and functions. It will be clearly understood that in the several instrumentalities which depend upon cams and cam rollers for their action, the cam rollers are held against the cams by springs, or other equivalent devices, which are not herein shown in detail, in order not to complicate unnecessarily the drawings. It will also be understood that my invention is not confined in any way to the specific mechanism employed for accomplishing the various functions of the machine, but is entitled to a fair range of equivalents within the terms of the annexed claims.
- More specifically referring to the operation of the folding devices above described, it is to be understood that the forming plate 100 does not firmly grip or bite the blank when in its horizontal position, so as to interfere with the withdrawal of the blank by the gripper folder 135. On the contrary, the stationary part of table 55 has its upper surface so formed as to prevent such gripping, said surface having only one or two high points which would actually be engaged by the plate 100, the remainder of said surface being depressed or rounded off from said high points, as shown in Fig. 6. Furthermore, when the gripper folder 135 becomes operative, the movable section 110 of table 55 has started to move down, so that there is no pinching or gripping of the envelop between said movable section and the plate 100. In this way the operation of the gripper folder 135 is greatly facilitated, it being clear that the resilient cushions 146, acting through the openings 109 in the edge of plate 100, can firmly seize and press the folded edge of the partly formed envelop into gripping contact with the periphery of carrying cylinder 133.
- I claim,
1. A machine for making window envelops, comprising a support for an envelop blank, a suction member adapted to apply a patch of transparent paper to said blank on said support, a stripping plate adapted to strip said patch from said suction member and to deposit said patch on said blank, a pair of folding plates adapted to fold the

side flaps of the blank over said stripping plate, and means for actuating said suction member, said stripping plate and said folding plates.

5 2. A machine for making envelops, comprising a support for the body of an envelop blank, said support having an opening therein, a lower creasing plate adapted to pass through said opening under part of 10 said blank, an upper creasing plate adapted to clamp the body of said blank on said support, a projection carried by one of said creasing plates, and a notch in the other creasing plate, whereby the coöperation of 15 said plates effects the creasing of the seal flap of the blank, a pair of folding plates adapted to fold the side flaps of the blank over said upper creasing plate, and means for operating said creasing plates and said 20 folding plates.

3. A machine for making envelops, comprising a support for the body of an envelop blank, a movable plate in advance of said support and adapted to receive on its upper 25 surface the back flap of the blank, an upper creasing plate adapted to clamp the body of the blank on said support, a lower creasing plate adapted to pass through an opening in said support under part of said blank, 30 the coöperating edges of said movable plate and said upper creasing plate being adapted to crease the said back flap therebetween, and the coöperating faces of said upper and lower creasing plates being adapted to 35 crease the seal flap of the blank therebetween, a pair of suitable folding plates adapted to fold the side flaps of the blank over said upper creasing plate, and means for actuating said creasing plates and said 40 folding plates.

4. In a machine for making envelops, a support for an envelop blank, a plate in advance of said support and adapted to receive on its upper surface the back flap of 45 the blank, an upper creasing plate adapted to act as a clamp for the blank on said support, the coöperating edges of said plates being adapted to crease the back flap therebetween, and a mechanism for folding said 50 back flap adapted to coöperate with said support to engage a blank thereon and fold the same, and means for moving said first mentioned plate out of the path of said back flap folding mechanism during the operation 55 of folding said back flap.

5. In a machine for making window envelops, means for feeding envelop blanks through the machine, a support for said blanks, a patch applying mechanism adapted to apply patches of transparent paper to successive blanks on said support, means for registering said blanks with said patch applying mechanism, said registering means including a pair of frontal stops adapted to 60 arrest the forward motion of said blanks,

and means for creasing the back flaps of the blanks, said creasing means including a movable plate in advance of said support and said frontal stops being mounted on said creasing plate.

70

6. In a machine for making envelops, a support for envelop blanks, an oscillating plate in advance of said support and adapted to receive on its upper surface the back flaps of said blank, an upper creasing plate 75 coöperating with said support and adapted to clamp said blanks thereon, the coöperating edges of said plates being adapted to crease the said back flaps therebetween, preliminary to their being folded, and a 80 mechanism for folding said back flaps adapted to coöperate with said support to engage a blank thereon and fold the same, said oscillating plate being movable out of the path of said back flap folding mechanism during the operation of folding said 85 back flaps.

85

7. In a machine for making envelops, a mechanism for folding the back flaps of the envelop blanks, comprising a support for 90 said blanks, a suitable clamp adapted to hold said blanks on said support, a rotary carrier, a gripper folder mounted on said rotary carrier, said gripper folder being adapted to seize and fold said back flaps 95 over said clamp on said support, thereby also closing the same, and to remove the folded blanks from said clamp and off said support, and means for actuating said clamp and said gripper folder.

100

8. In a machine for making window envelops, means for conveying a transparent patch to an envelop blank, to cover a window opening therein, an oscillating member for stripping said patch from said conveying means, and folding devices, coöperating with said oscillating member, for folding the flaps of the blank.

105

9. In a machine for making envelops, a support for an envelop blank, a movable 110 plate in advance of said support, over which the back flap of the blank projects, a member movable into contact with the upper surface of the blank on said support, and coöperating with said support to crease the 115 seal flap of said blank, and with said movable plate to crease the back flap of said blank.

10. In a machine for making envelops, a support for an envelop blank, a movable 120 plate in advance of said support, over which the back flap of the blank projects, a member movable into contact with the upper surface of the blank on said support, and coöperating with said support to crease the 125 seal flap of said blank, and with said movable plate to crease the back flap of said blank, and means coöperating with said member for holding the side flaps of said blank.

130

11. In a machine for making envelops, means for stationarily supporting an envelop blank, with a flap thereof overhanging said supporting means, a rotating carrier adjacent said overhanging flap, and unitary means on said carrier operable during the rotation thereof, for folding back said flap, and for coöperation with said carrier to seize the edge of the blank thus folded, 10 and to remove said blank from said support.
12. In a machine for making envelops, means for stationarily supporting an envelop blank, with a flap thereof overhanging said supporting means, a rotating carrier adjacent said overhanging flap, a member 15 movable into contact with the upper surface of a blank on said support, and oscillating means on said carrier, operable during the rotation thereof, for coöperation with said member to fold said overhanging flap.
13. In a machine for making envelops, means for stationarily supporting an envelop blank, with a flap thereof overhanging said supporting means, a rotating carrier adjacent said overhanging flap, a member 25 movable into contact with the upper surface of a blank on said support, and oscillating means on said carrier, operable during the rotation thereof, for coöperation with said member to fold said overhanging flap, and for coöperation with said carrier, to seize the edge of the blank thus folded and to remove said blank from said support.
14. In a machine for making window envelops, a mechanism for gumming the seal flaps of the envelop blanks, comprising a carrier for said blanks, a shaft having a fixed axis of rotation, revolving arms connected to said shaft, radially movable arms 35 adapted to slide in said revolving arms, a seal flap gummer connected to said radially movable arms at the outer ends thereof, rollers on said gummer, and a guiding cam loosely fitting on said shaft and adapted to 40 suitably guide said rollers on said gummer, thereby bringing said gummer into contact with the seal flaps of said blanks on said carrier, combined with a mechanism adapted to automatically turn said guiding cam on said shaft into a position whereby it will 45 guide said rollers to bring said gummer out of contact with said carrier in the absence of a blank thereon.
15. In a machine for making window envelops, a mechanism for gumming the seal flaps of the envelop blanks, comprising a carrier for said blanks, a shaft having a fixed axis of rotation, a radially adjustable 55 rotary gummer connected thereto, rollers on said gummer, a guiding cam loosely fitting on said shaft and adapted to control the motion of said gummer by means of said rollers in contact therewith and to bring said gummer into and out of contact with said carrier 60 by changing the position of said guiding
- cam on said shaft, and a mechanism for automatically controlling the position of said guiding cam on said shaft, said mechanism comprising a rotary disengagement cam, a roller operatively connected to said guiding 70 cam, said roller being normally out of contact with said disengagement cam and adapted to be brought into contact therewith, and automatic means for bringing said roller into contact with said disengagement cam in 75 the absence of a blank on said carrier, thereby changing the position of said guiding cam on said shaft.
16. In a machine for making envelops, a mechanism for gumming the seal flaps of partly made envelops, a seal flap folding mechanism and a means for transmitting said partly made envelops from said gumming mechanism to said folding mechanism, said seal flap folding mechanism comprising a rotary carrier for said partly made envelops, a gripper folder mounted on said carrier, said gripper folder being adapted to seize the partly made envelop and fold the seal flap thereof against said carrier, without closing said flap, and said transmitting means including a stationary support for said partly made envelops, to rest edgewise thereon, said support being arranged adjacent to said folding mechanism, and a member 85 adapted to coöperate with said support to bring the partly made envelop within reach of said seal flap folding mechanism.
17. In a machine for making envelops, a mechanism for folding the seal flaps of partly made envelops, comprising a rotary carrier, a suitable gripper folder mounted on said carrier, a movable plate operatively situated adjacent to said carrier and adapted to bring said envelop with the open seal flap 90 within reach of said gripper folder, on the outside of said carrier, during a proper phase of the motion of said gripper folder, and to coöperate therewith in folding said seal flap, said gripper folder being adapted 95 to fold said seal flap over the edge of said plate without closing the seal flap, and said carrier, in its rotation, being adapted to move said gripper folder, thereby carrying said folded envelop off said plate.
18. In a machine for making envelops, a seal flap folding mechanism, means for actuating said mechanism, a support arranged adjacent to said folding mechanism for the partly made envelop to rest edgewise thereon, a suitable member for said partly made envelops to lean against flatwise, and a plate adapted to coöperate with said support and said member to bring the upper part of said partly made envelop within reach of said seal flap folding mechanism.
19. In a machine for making envelops, a back flap gumming mechanism, a back flap folding mechanism and a seal flap gumming mechanism, combined with a cylindrical 120 125 130

pressing plate for the back flaps of the envelop blanks, said folding mechanism including a rotary carrier for the blanks, and a gripper folder mounted on said carrier, said gripper folder being adapted to fold said back flaps, and said pressing plate being adapted to coöperate with said carrier in pressing said back flaps therebetween.

20. In a machine for making envelops, a back flap gumming mechanism, a back flap folding mechanism and a seal flap gumming mechanism, combined with a cylindrical pressing plate for the back flaps of the envelop blanks, said folding mechanism including a rotary carrier and a gripper folder mounted on said rotary carrier, said gripper folder being adapted to fold said back flaps, and said pressing plate being connected to said seal flap gumming mechanism and adapted to rotate therewith and to coöperate with said carrier in pressing said back flaps therebetween.

21. In a machine for making envelops, the combination with means for folding the flaps of an envelop blank, of means for supporting said blank during the folding operations, a portion of said supporting means being movable to effect the creasing of one of the flaps of the blank, and means for engaging the rear edge of the blank on said support to register the same in advance of the creasing operation of said movable portion.

22. In a machine for making envelops, the combination with means for folding the flaps of an envelop blank, of means for supporting said blank during the folding operations, a portion of said supporting means being movable to effect the creasing of one of the flaps of the blank, an actuating means for said movable portion, and registering devices for the blank, yieldingly connected to said actuating means, whereby the initial movement of said actuating means registers said blank.

23. In a machine for making envelops, the combination with means for folding the flaps of an envelop blank, of means for supporting said blank during the folding operations, a portion of said supporting means being movable to effect the creasing of one of the

flaps of the blank, an actuating means for said movable portion, and means for arresting the movement of said registering devices, substantially coincident with the operation of said movable portion by said actuating means.

24. In a machine for making window envelops, a support for envelop blanks, a movable suction member adapted to apply patches of transparent paper to successive blanks on said support, and a stripping plate for said patches adapted to strip said patches off said suction member and to deposit said patches upon said blanks on said blank support.

25. In a machine for making window envelops, a support for envelop blanks, an oscillating support for patches of transparent paper, a movable suction member, an oscillating stripping plate, said suction member being adapted to pick up said patches from said patch support, one at a time, and move the same toward said blanks on said support, said stripping plate being adapted to strip said patches off said suction member and deposit said patches upon said blanks on said blank support, said patch support and said stripping plate being adapted to be turned out of the path of said suction member during its travel toward said blank support, and said stripping plate having suitable openings adapted to clear said patch support when turned out of the path of said suction member.

26. In a machine for making envelops, a cylindrical member rotating about a fixed axis and adapted to carry a blank on the surface thereof, a second member rotating about a fixed axis and providing a surface for co-operation with a flap of a blank on said first member to gum said flap, and means for automatically retracting the surface of one of said members, in the absence of a blank on said first rotating member.

Dated this twenty-first day of August, 1917.
